CLAIM

The ornamental design for a roasting basket, as shown and described.

DESCRIPTION

FIG. 1 is a top, left and front perspective view of a roasting basket showing my new design;

FIG. 2 is a rear elevational view thereof as seen in the direction of arrow 2 of FIG. 1;

FIG. 3 is a front elevational view thereof as seen in the direction of arrow 3 of FIG. 1;

FIG. 4 is a top plan view thereof, the bottom plan view thereof being identical to FIG. 4; and

FIG. 5 is a right side elevational view thereof, the left elevational side view thereof being the mirror image of FIG. 5.

FIG. 1

FIG. 2

FIG. 3

FIG. 4

FIG. 5
